(57) **CLAIM**

The ornamental design for a lamp, as shown and described.

DESCRIPTION

FIG. 1 is a front elevational view of our new design;
FIG. 2 is a top plan view thereof;
FIG. 3 is a perspective view thereof;
FIG. 4 is a bottom plan view thereof; and,
FIG. 5 is a left side elevational view, the right side elevational view being a mirror image thereof.
The broken lines in the drawings depict environmental subject matter only and form no part of the claimed design.

1 Claim, 5 Drawing Sheets
